UNITED STATES PATENT OFFICE.

JEREMIAH MUCKEY, OF GORIN, MISSOURI.

MOLD FOR CONCRETE CURBS FOR GRAVES.

1,024,646.

Specification of Letters Patent.

Patented Apr. 30, 1912.

Application filed June 24, 1911. Serial No. 635,103.

To all whom it may concern:

Be it known that I, JEREMIAH MUCKEY, a citizen of the United States, residing at Gorin, in the county of Scotland and State 5 of Missouri, have invented certain new and useful Improvements in Molds for Concrete Curbs for Graves, of which the following is a specification.

This invention relates to molds for forming concrete grave curbing and one of the 10 principal objects of the invention is to provide simple and efficient means for molding a rectangular curbing of concrete material all in a single piece which may be plain or 15 decorated, as desired.

Another object of the invention is to provide means for quickly molding concrete curbing in the form of a rectangular curb 20 made in a single piece or casting of any required size for protecting graves or for other purposes.

These and other objects may be attained by the means of the construction illustrated 25 in the accompanying drawings, in which—

Figure 1 is a top plan view of a mold made in accordance with my invention, said view showing a curbing in the mold; Fig. 2 is a top plan view of the mold with the curb removed and the inner member or core of 30 the mold collapsed or adjusted inwardly to permit its removal from the mold box or frame; Fig. 3 is a longitudinal section taken on the line 3—3 of Fig. 1 looking in the direction indicated by the arrow; Fig. 4 is a 35 longitudinal sectional view taken on the line 4—4 of Fig. 1 looking in the direction indicated by the arrow; Fig. 5 is a longitudinal sectional view taken on the line 5—5 of Fig. 2, looking in the direction indicated by the arrow; and Fig. 6 is a transverse vertical sectional view taken on the 40 line 6—6 of Fig. 1 looking in the direction indicated by the arrow.

Referring to the drawings, the numeral 1 45 designates a mold box or frame which may be of any required size depending upon the character of the curb to be molded, said frame being contracted at its upper side and flaring at its lower side as shown in the 50 drawing.

The collapsible core for molding the curbs 55 comprises four members 2, 3, 4 and 5, said members having angularly bent ends which are beveled as at 6, said beveled ends adapted to be adjustable, to expand and contract

the core. The members 2 and 3 are each provided with a lug 7. A pivot latch 8 is connected to a curved lever 9 near the pivot point 10 of the lever said lever being pivoted at 10 upon a lug 11 secured to the members 4 and 5 at opposite ends of the core upon the inside thereof. Connected to the curved levers 9 are suitable links or bars 12, said bars being pivoted at their meeting ends upon a bolt 13 which extends through a lever 14 provided with a circular head, the fulcrum of the lever being eccentric to the head. The lever 14 is pivoted at 15 upon a pin or rivet which passes through an elongated slot 24 in the side 4 of the core. A 70 link 16 is provided with a strap passing around the eccentrically mounted circular end of the lever 14, said link being provided with a shank 17 provided with notches 18 near the end thereof. The shank 17 is adjustable to regulate the initial positions of the sides 2 and 3, 4 and 5, respectively. The members 2 and 3 are mounted to slide longitudinally one upon the other by means of the slot 20 and pins 21 while the ends of 80 the members are also permitted to slide upon the pins 22 extending through slots 23 as shown more clearly in Fig. 6. The members 4 and 5 are mounted to slide longitudinally one upon the other by means of 85 the slot 24 and pins 15 and 25. The links may be provided with perforations *a* for permitting adjustment.

The operation of my invention may be briefly described as follows:—With the mold in the condition shown in Fig. 2 the concrete material comprising crushed rock, sand, gravel, white sand or granitoid mixed with cement and water is poured in through the space *b* between the mold box 1, and the collapsible core. It will be understood that any desired thickness of curb may be made with this apparatus and that any size of curbing may be molded depending upon the size of the mold box 1 and the relative dimensions of the collapsible core. After the concrete has been placed in the space *b*, the lever 14 is operated to expand the core and to press the material against the inner wall of the box 1. After the material has become set, the core is collapsed by moving the lever 14 in the opposite direction after which the collapsible core may be removed. The mold box 1 may be then lifted from the curb and the latter permitted to dry. 105 110

My invention is comparatively simple in construction, is quick in operation, and will mold grave curbings in a single casting.

What I claim is:

- 5 1. A mold for molding rectangular concrete curbing comprising a mold box and a collapsible core comprising a plurality of members having beveled ends, curved levers, pivoted upon lugs secured to the members
  - 10 at opposite ends of the core upon the inside thereof, latches connected to said levers and to the members forming one side of said core, links pivoted to said curved levers and a lever provided with a circular head, the fulcrum of the lever being eccentric to the head for expanding and contracting said members.
  - 15 2. A mold for concrete curbing comprising a mold box, a collapsible core comprising four members having beveled ends mounted to slide one upon the other, curved levers pivoted to the lugs secured to the members at opposite ends of the core, upon the inside thereof the end members, latches
  - 20 connected to said curved levers and removably connected to the members at one side of said core, links connected to said curved levers, said links being pivoted at their inner ends to a bolt secured to a lever having an eccentrically fulcrumed circular head said
  - 25
  - 30
- lever being secured to one side of the core, a lever provided with a circular head, the fulcrum of the lever being eccentric to the head for operating the core and a link having a strap passing around the eccentrically mounted head of the last mentioned lever, the shank of said link adjustably connected to one of the side members.
3. A mold for concrete curbing of rectangular form comprising a mold box, a collapsible core comprising four angular members having beveled ends mounted to slide one upon the other, curved levers pivoted to members at opposite ends of the core for operating said members, links connected to said curved levers, latches connected to said levers and to lugs upon the members forming one side of said core, a lever having an eccentrically mounted circular head for operating said links, and a link having a strap passing around the eccentrically mounted head of the last mentioned lever said link being adjustable on one side of the core.

In testimony whereof I hereby affix my 55
signature in presence of two witnesses

JEREMIAH TUCK.
